E. L. DOUGLASS

TEMPERATURE REGULATING SYSTEM FOR HOUSES

Filed Sept. 30, 1922

UNITED STATES PATENT OFFICE.

EDWARD L. DOUGLASS, OF JACKSBORO, TEXAS.

TEMPERATURE-REGULATING SYSTEM FOR HOUSES.

Application filed September 30, 1922. Serial No. 591,533.

To all whom it may concern:

Be it known that I, EDWARD L. DOUGLASS, a citizen of the United States, residing at Jacksboro, in the county of Jack and State 5 of Texas, have invented certain new and useful Improvements in Temperature-Regulating Systems for Houses, of which the following is a specification.

This invention relates to systems for 10 regulating the temperature of the air in a room or house and has special reference to an improved cooling and heating system.

It is a well understood fact that the temperature of the air in a well, a ditch or below the surface of the ground is usually 15 very much cooler than the corresponding summer temperature and warmer than the usual winter temperature, especially in the latitude of the temperate zone.

20 One important object of the invention is to provide an improved and novel means for utilizing these physics laws in the heating of a house in winter time and in the cooling of a house in the summer time.

25 A second important object of the invention is to provide a novel arrangement of such means which may be economically installed and which will also be economical in operation.

30 With the above and other objects in view as will be hereinafter apparent, the invention consists in general of certain novel details of construction and combinations of parts hereinafter fully described, illustrated 35 in the accompanying drawings and specifically claimed.

The accompanying drawing is a view partly in elevation and partly in section showing the application of the device to 40 a typically indicated building.

In the embodiment of the invention herein illustrated there is disclosed an air pump 10 which may be provided with a belt pulley 11 for connection of a belt 12 to a 45 motor 13 here shown as an electrical motor. It will be obvious that other means may be utilized for operating the pump 10 and it will be seen from what follows, that the particular means employed may be varied

at will without departing from the spirit 50 of the invention.

The ground, or earth is indicated at 14 and buried a suitable distance below the surface is a tank 15 for storage purposes. This tank is buried sufficiently far below 55 the surface of the ground and that which is at atmospheric temperature above the ground will have little, or no effect in the stratum in which the tank is buried. The tank 15 is connected to the pump 10 by 60 means of a pipe 16 and from this tank leads a pipe 17 which is connected to a pipe, conduit or coil 18 located in a well, ditch or other opening under the surface. This coil may either be located in the water in 65 a well, or just above the same. From the coil 18 a pipe 20 leads to the building 21 being there conducted into the various rooms and having in each room one or more outlets, and there discharged for cooling or 70 heating. This tank being buried has the effect of cooling or warming the air before it leaves the tank, this being a preliminary cooling or warming. From the tank air passes to the coil 18 where it is still further cooled or warmed and from thence it passes through the pipe 20 to the several 75 outlets 22. If desired, my system, may be used without the tank 15.

Having thus described the invention, 80 what is claimed as new, is:—

A system for stabilizing the atmospheric temperature of a building structure comprising a well tapping a subterranean volume of water, a tank buried in the earth 85 at a location spaced from the side of the well, pumping means for forcing atmospheric air, a pipe for conducting the air from the pump to the tank, the transverse sectional area of the pipe being less than 90 the transverse sectional area of the tank, a second pipe leading from the tank at a point which is spaced from the point of entrance of the first mentioned pipe with the tank, the second mentioned pipe being 95 substantially of the same diameter as that of the first mentioned pipe and being less in transverse sectional area than the trans-

verse sectional area of the tank, the second mentioned pipe having a coil section disposed in the well and extending below the level of the bottom of the tank, said coil being above the surface level of the water in the well and lying within the radiating zone affected by the temperature of the water, the second mentioned pipe having

a section leading from the coil and entering the building and provided with an air ¹⁰ opening which is located within the building.

In testimony whereof I affix my signature.

EDWARD L. DOUGLASS.
